UNITED STATES PATENT OFFICE.

LOUIS A. CASGRAIN, OF BEVERLY, MASSACHUSETTS, ASSIGNOR TO UNITED SHOE MACHINERY COMPANY, OF PATERSON, NEW JERSEY, A CORPORATION OF NEW JERSEY.

WORK-SUPPORT.

1,030,971.

Specification of Letters Patent.

Patented July 2, 1912.

Application filed January 31, 1910. Serial No. 541,137.

To all whom it may concern:

Be it known that I, LOUIS A. CASGRAIN, a citizen of the United States, residing at Beverly, in the county of Essex and State of Massachusetts, have invented certain Improvements in Work-Supports, of which the following description, in connection with the accompanying drawings, is a specification, like reference characters on the drawings indicating like parts in the several figures.

This invention relates to work supports for fastening inserting machines of the character employed in the manufacture of boots and shoes.

It is an important object of this invention to provide a work support for a machine of the character referred to by means of which fastenings may be inserted along the margin of a shoe sole.

The work support illustrated in the accompanying drawing is designed especially for use in inserting fastenings along the shank of a welt shoe for the purpose of reinforcing the outseam at this point. It frequently happens, after a shoe has been worn for some time, that the stitches of the outseam break in the shank and thus allow the outsole to split away from the welt.

This result is due chiefly to the fact that the constant bending of the shank portion of the sole during wear subjects the stitches to severe strains; but the action of the shank stiffener also contributes to this end since it prevents the distribution of the bending movement over the entire shank and tends to concentrate the bending at each end of the stiffener, particularly at the end near the juncture of the shank and forepart.

Furthermore, the shank stiffener tends to press the outsole away from the insole and the welt. It has been proposed to reinforce the outseam to prevent the splitting of the outsole away from the welt as described by

placing a line of fastenings along the shank. The "double clench" fastenings handled by the machine shown in the United States Patents No. 669,023, dated Feb. 26, 1901 and No. 693,686 dated Feb. 18, 1902, are especially adapted for this purpose, since the clenched ends of the fastenings hold the welt and outsole firmly together.

The present invention aims to provide a work support especially adapted to be used on machines of the character designated for

the purpose of driving fastenings along the outseam.

To this end one feature of the invention consists in a novel work engaging tip having one or more clenching cavities, the tip being shaped to enter the crease between the welt and upper so that the fastenings may be placed close to the stitches. Preferably the tip is provided with a plurality of clenching cavities any one of which may be adjusted in operative position to the fastening inserting mechanism as another becomes worn.

Another feature of the invention consists in the provision with a work sustaining member, of a latch operatively associated with said member and means operating through said latch to move the member in timed relation to the fastening inserting operation. The latch preferably is so arranged that it normally retains the work sustaining member in operative position, but when tripped permits the member to be moved into inoperative position.

A further feature of the invention consists in a construction whereby the work engaging tip may be adjusted in any direction necessary to position it accurately with reference to the work abutment of the fastening inserting mechanism. In the preferred embodiment of the invention the work sustaining member is arranged for adjustment both vertically and laterally with respect to the abutment and the work engaging tip is made adjustable on the work sustaining member in a direction at substantially right angles to both directions of adjustment of said member.

The invention also comprises other features including certain details of construction and combinations and arrangements of parts which will later be described and claimed.

Referring now to the drawings, Figure 1 is a side elevation of the upper portion of a double clench machine provided with the novel work support of the present invention. Fig. 2 is a cross sectional view taken on the line 2—2, Fig. 1, and Fig. 3 is a cross section showing a detail of construction to be referred to later.

The machine illustrated is substantially like that described and shown in the United States Patent No. 693,686 and reference should be made thereto for a detailed de-

scription of the construction and operation of the fastening inserting mechanism. As the present invention is concerned primarily with the work support such description is unnecessary here.

The post 2 supports the entire fastening inserting mechanism and is itself supported adjustably on a standard 4 by means of the bolts 6. A support or bracket 8 is secured 10 to the post 2 near its lower end by bolts 10, the post having a transverse groove formed therein to receive a tongue 12 on the bracket. By this construction the bracket is adapted to fit onto the post in place of the regular 15 horn. The bracket comprises two arms extending forwardly and upwardly and a rib 14 connecting said arms. Supported in the forward ends of the bracket arms is a pivot bolt 16, retained in position by suitable nuts 20 and washers, and a work sustaining lever 18 of bell crank form is pivoted on and is adjustable axially of said bolt. A draw bolt 20 extending through the lever and engaging the bolt 16 (see Fig. 3) serves to secure the 25 lever firmly in adjusted position. The forward end of the bell-crank lever has a hole drilled therein and its lower side is slotted longitudinally to form a clamping portion in which a work engaging tip is adjustably 30 received, a bolt 24 serving to clamp the tip securely in place.

The work engaging tip comprises a body portion 22, a shank 26 extending therefrom and an adjustable plate 28 secured on the 35 upper side of the body portion by means of a screw 30. One or more dowel pins extending into holes 32 in the plate 28 prevent the plate from turning. The plate as shown in the drawings is of pentagonal form with its 40 corners rounded, but it may be circular or of any other suitable shape. A plurality of clenching cavities 34 are formed in the upper face of the plate, one cavity being located adjacent each corner, and as one 45 cavity becomes worn another may be adjusted in operative position under the work abutment 36 of the fastening inserting mechanism by merely loosening the screw 30 and changing the angular position of the plate. In order that the fastenings may be 50 inserted close to the stitches in the shank of the shoe, the plate 28 is formed with a relatively thin lip projecting entirely around its upper edge. This lip may be forced into 55 the crease between the sole and upper of a shoe as it is placed sole upward on the work supporting tip so as to bring the clenching cavities very close to the line of stitches; and the plate is cut away below the lip so as 60 not to interfere with the upper of the shoe. Moreover the polygonal shape of the plate permits the operator to rock the shoe about the rounded corner adjacent each clenching cavity to position the shoe correctly for the 65 driving of the fastenings. The lever 18 and

tip 22 are normally held in the position shown in full lines in Fig. 1, by a latch pivoted to the rearmost end of the lever. This latch has a forwardly extending arm 40 curved downwardly below the bracket rib 14 and is provided on its forward end with an enlargement 42 through which is threaded an adjusting screw 44 engaging the rib 14. A friction plunger 46 located in a recess in the enlargement 42 is pressed against the screw 44 by a coil spring also positioned in the recess and operates to prevent accidental turning of the adjusting screw. It will be clear from Fig. 1 that turning the screw 44 in or out will result in raising 70 or lowering the tip 22. The latch is also provided with a second arm 48 that normally engages the stop 50 projecting laterally from an arm 52, one end of which is mounted on the pivot bolt 16 and the other end of which is pivotally connected to a rod 54 operated from the fastening inserting mechanism. The latch is normally held in the position shown in Fig. 1, with its arm 48 engaging the stop 50 and the adjusting 75 screw 44 abutting against the rib 14, by a spring 56 connected at one end to the latch and at its opposite end to a stationary bracket 58. When the latch is tripped by pressing downwardly on the screw 44 or member 46, the spring 56 turns the bell crank lever and latch about the pivot bolt 16 into the position indicated by the dotted lines in Fig. 1. The work support is then in convenient position for the workman to 80 make adjustments either to the support itself or to the fastening inserting mechanism. The latch may be returned to its operative position by merely raising the tip 22.

In order to keep the lever 18 and arm 52 in a constant axial relation to each other the hub portion of the arm is provided with a boss 60 having a guideway formed therein to receive a shouldered projection 62 on the lever 18. As the lever is adjusted axially of the pivot 16 the arm 52, therefore, must move with it. Lubricating material may be supplied to the pivot bolt 16 through the holes 64 formed in the bracket arms 8.

It will be clear that by means of the various adjustments above described the work engaging tip may be moved in any direction necessary to position the clenching cavities accurately with reference to the work abutment 36.

In operation, the rod 56 is moved in timed relation to the fastening inserting operation, and this movement is transmitted through the arm 52, stop 50, latch arm 48 and lever 18 to the tip 22 to clamp the work firmly between the plate 28 and work abutment 36 during the period in which the fastening is being driven and clenched. Between the inserting of successive fastenings, the rod 54 is moved upwardly and the spring 56 100

operates through the lever 18 to lower the work engaging tip and permit the operator to feed the work over the plate 28 into position for receiving the next fastening.

5 It will be understood that the work support of this invention is not limited in its application to a machine of the type shown or to the particular use herein emphasized, but that it may be used with other types of 10 fastening inserting machines, as, for instance, on staple fastening machines of the type shown in United States Patent No. 899,093, dated September 22, 1908, and for other purposes than that specified.

15 Having described my invention, what I claim as new and desire to secure by Letters Patent of the United States is:—

1. In a fastening inserting machine having a work abutment the combination of a 20 support, a lever pivoted thereon, said lever having a work engaging tip, means for giving said lever movements to cause it to clamp the work against said abutment and to release it again comprising a latch arranged in operative relation to said lever, and means operating through said latch to move the lever in timed relation to the fastening inserting operation, said latch being mounted for movement to free the lever 25 from the operation of said means.

2. In a fastening inserting machine having a work abutment the combination of a rigid support, a work supporting lever pivoted thereon, a member arranged for movement in timed relation to the fastening inserting operation, a latch pivotally connected to said lever and arranged to transmit movement from said member to said lever to cause the lever to clamp the work 35 against said abutment and to release it again, and means for yieldingly holding said latch in engagement with said member.

3. In a fastening inserting machine having a work abutment the combination of a rigidly supported bracket, a lever fulcrumed thereon, a work supporting tip rigid with said lever, means whereby the tip may be adjusted relative to the work abutment, and means for moving said lever in timed relation to the fastening inserting operation to clamp the work between said tip and work abutment.

4. In a fastening inserting machine having a work abutment the combination of a rigid support, a lever pivoted thereon, said lever having a work engaging tip, a member arranged for movement in timed relation to the fastening inserting operation and a latch operatively arranged between said lever and member whereby the tip is moved to clamp the work against the work abutment during the inserting of the fastening, said latch being constructed and arranged for movement out of engagement with said member.

5. In a fastening inserting machine having

a work abutment the combination of a support, a lever fulcrumed thereon, a work supporting tip adjustably secured to said lever and means whereby said lever may be adjusted pivotally and horizontally to vary 70 the position of said tip relative to said work abutment.

6. In a fastening inserting machine having a work abutment the combination of a work sustaining member adjustable vertically and laterally with reference to said work abutment and a work engaging tip carried by said member and arranged for adjustment in a direction at substantially right angles to both directions of adjustment of the work sustaining member.

7. In a fastening inserting machine the combination of a support, a lever pivoted thereon, a work engaging tip carried by said lever, a latch pivoted to said lever, adjusting means for the lever carried by said latch and means operating through said latch to move said lever and tip in timed relation to the fastening inserting operation.

8. In a fastening inserting machine the combination of a support, a work supporting lever fulcrumed thereon, an adjustable latch arranged to hold said lever normally in operative position and movable to free the lever, and means operating through said latch to rock said lever on its fulcrum in timed relation to the fastening inserting operation.

9. In a fastening inserting machine the combination of a support, a lever pivoted thereon, a work supporting tip carried by said lever, a latch arranged to engage a stationary member to hold said lever normally in operative position whereby when said latch is tripped the lever is free to move to inoperative position, and means operating through said latch to move said lever in timed relation to the fastening inserting operation.

10. In a fastening inserting machine the combination of a support, a lever pivoted thereon, a work supporting tip carried by said lever, a latch arranged to hold said lever in operative position, a spring acting on said latch to hold it in operative position but arranged to move the lever to inoperative position when the latch is tripped.

11. In a fastening inserting machine the combination of a rigidly supported bracket, a lever pivoted thereon, a work supporting tip rigidly mounted on the forward end of said lever, a latch pivoted to the other end of the lever, a member movable in timed relation to the fastening inserting operation, said latch when in operative position having one arm carrying an adjusting screw engaging a portion of said bracket and another arm engaging said member and means for yieldingly holding said latch in operative position.

- 4
12. In a fastening inserting machine the combination of a bracket having two parallel arms and a rib connecting said arms, a pivot bolt supported in said arms, a bell 5 crank lever mounted on said bolt and adjustable axially thereof, a work supporting tip adjustably and removably secured to the forward end of said lever, an arm mounted on said bolt, said arm having a stop projecting therefrom, a latch pivoted to the rear end of said bell crank lever, said latch having an arm arranged to engage said stop and also having an arm normally extending in front of said rib, an adjusting screw extending through the last mentioned arm and engaging said rib and a spring connected to said latch tending to hold the latch in engagement with the stop but arranged to turn said lever and latch about the axis of 20 said bolt when the latch is tripped.
13. A tip for a work support comprising a plate provided on its upper side with a plurality of clenching cavities, said plate being cut away from its upper edge to form
- a lip adapted to enter the crease between 25 the welt and upper of a shoe, a body on which said plate is adjustable to bring any one of said cavities into operative position and a shank extending from said body whereby the tip may be secured to a suitable 30 support.
14. A tip for a work support comprising a polygonal plate having its corners rounded and provided on its upper side with a clenching cavity adjacent to each corner, said plate 35 having a thin upper edge adapted to enter the crease between the welt and upper of a shoe, a body portion on which said plate is angularly adjustable and a shank projecting from said body portion arranged to be secured in a suitable holder. 40

In testimony whereof I have signed my name to this specification in the presence of two subscribing witnesses.

LOUIS A. CASGRAIN.
